UNITED STATES PATENT OFFICE.

LOUIS F. KLOEPFEL, OF BOSTON, MASSACHUSETTS.

MUSICAL WIND INSTRUMENT.

1,122,207.

Specification of Letters Patent.

Patented Dec. 22, 1914.

Application filed June 19, 1913. Serial No. 774,544.

To all whom it may concern:

Be it known that I, LOUIS F. KLOEPFEL, a citizen of the United States, residing at Boston, in the county of Suffolk and State 5 of Massachusetts, have invented new and useful Improvements in Musical Wind Instruments, of which the following is a specification.

This invention relates to improvements in 10 musical wind instruments, the object of the invention being to produce a wind instrument for use in small orchestras or bands where one musician is obliged to play two or more instruments, so that one musician 15 may play the cue notes in arrangements of music for small orchestras. For instance a musician may play with my improved instrument the parts arranged for a cornet and for the French horn and by the use of different mouth-pieces he may play the cue 20 notes for the bassoon, trombone and French horn. To accomplish these ends I combine two wind instruments of different styles or character, each of said instruments having 25 a mouth piece, the mouth pieces, however, varying in the formation of their interior bores, but the rims of both mouth pieces being substantially duplicates one of the other and located adjacent to each other, so that 30 as the occasion requires the musician may first play on one instrument and then on the other by changing from one mouth piece to the other, and to obtain a still greater variety the musician may change one of the 35 mouth pieces as may be required.

In the instrument as illustrated and described in the following specification one of the wind instruments is constructed after the usual style of the cornet or trumpet 40 while the other instrument has a specially constructed tube leading from the mouth piece to the third valve and a specially constructed and arranged bell, whereby the sounds are directed outwardly from said bell 45 at a different angle from that in which the sounds are directed from the bell of the cornet or trumpet. The tone produced by the particular construction of the tube leading from the mouth piece to the third valve 50 of my specially constructed wind instrument and the downwardly extending bell is a close

resemblance to the tone of a French horn, and the mouth piece is also constructed to aid in this production of tone, but the rim of the mouth piece and the rim of the cornet 55 mouth piece are substantially duplicates.

Another object of the invention is to so construct the instrument that the two independent wind instruments may be readily disconnected from each other and used as 60 separate instruments if so desired.

The invention consists in the combination and arrangement of parts set forth in the following specification and particularly pointed out in the claims thereof. 65

Referring to the drawings: Figure 1 is a side elevation of a wind instrument constructed in accordance with my invention, one of the mouth pieces being broken away to illustrate the construction thereof, and 70 shown in section. Fig. 2 is a plan view of the same, the other mouth piece being shown in section. Fig. 3 is a sectional elevation taken on line 3—3 of Fig. 2. Fig. 4 is a detail sectional plan of the bracket and levers whereby the two wind instruments are 75 joined together.

Like numerals refer to like parts throughout the several views of the drawings.

In the drawings, 5 is a wind instrument 80 similar to the ordinary cornet. 6 is another wind instrument, known as the "corneto-corno." The instrument 5 comprises a series of valves 7, 8 and 9, constituting the first, second and third valves, respectively, of the 85 cornet. These valves are provided with casings 10, 11 and 12, respectively, and are constructed in the usual manner. The third valve 9 is connected to the second valve 8 by a tube 13 and the valve 8 is connected to 90 the valve 7 by a tube 14 in the usual well known manner. The third valve 9 is supplied with the usual U-shaped tone and one half tube 15, the valve 8 is supplied with the usual half tone tube 16 and the valve 7 is 95 supplied with the usual U-shaped one tone tube 17. The mouth piece 18 has a rim 19 and is connected to the valve 9 by a tube 20. A bell 21 is connected by a conical tubular extension 22 to a tube 23, which, in its turn, 100 is connected to the valve 7.

The corneto-corno 6 comprises a series of

valves 24, 25 and 26, being the valves known as the first, second and third valves of the instrument. These valves are provided, respectively, with casings 27, 28 and 29. The 5 valve 26 is connected to the valve 25 by a tube 30, while the valve 25 is connected to the valve 24 by a tube 31 in the usual well known manner. The valve 26 is provided with a tone and one-half tube 32. The valve 10 25 is provided with a half tone tube 33 and the valve 24 is provided with a one tone tube 34. The instrument 6 is provided with a mouth piece 35 which has a rim 36 thereon and is connected by a tube 37 to the third 15 valve 26. Said tube has a plurality of U-shaped bends 38, 39 and 40 formed therein and connects at 41 with the valve 26. A bell 42 is connected to the valve 24 by a tube 43 and a conical tubular extension 44, said conical tubular extension being bent at an angle 20 at 45, so that the sound waves are directed from the bell 42 in a direction substantially at right angles to the direction in which the sound waves are directed from the bell 21 25 and said sound waves are directed from the bell 42 substantially at right angles to the mouth piece tube 37.

It will be noted that while the rims 19 and 36 are substantially duplicates as to 30 size and form, the interior bore 46 of the mouth piece 18 is much shorter than the bore 47 of the mouth piece 35, that is, the cup of the mouth piece of the corneto-corno is much deeper than that in the trumpet mouth piece 35 before it arrives at its smallest diameter where it joins the tube leading to the third 40 valve. The effect of this difference in construction of the mouth piece is that it assists in the production of a tone similar to that of a French horn.

The rims 19 and 36 being substantially duplicates of each other enables the same musician to play either one of the two instruments, and the position of one adjacent 45 to the other enables him to change from one to the other readily. It is well known to those skilled in the art of playing wind instruments that the same musician could not take up the ordinary French horn and play 50 that and the bassoon or trombone, but with the instrument hereinbefore described he can play either of the instruments, the cornet or the corneto-corno, and obtain the effect of playing a cornet and a French horn without any difficulty by simply changing from one mouth piece to another, and if he desires to obtain the effect of a bassoon 55 or trombone, he can do so by removing the mouth piece used to produce the tone of the 60 French horn with the corneto-corno and inserting a different shaped mouth piece—that is a mouth piece with a different shaped interior bore but having the same shaped rim.

In order to enable either of the instruments to be used as a single instrument, I

have detachably connected the two together by means of a bracket 48 (see Figs. 3 and 4) which is interposed between the casings 10, 11 and 12 and the series of casings 27, 28 and 29. Said bracket has fastened to opposite sides thereof segmental plates 49 and 50 which bear against the casings 11 and 28, respectively. A pair of levers 51 and 52 are pivotally mounted at 53 and 54, respectively, upon the bracket 48. These levers 75 are provided at their outer ends with segmental plates 55 and 56, respectively, which bear against the casings 12 and 10 respectively, and are held thereagainst by torsional springs 57 and 58. The levers 51 and 80 52 are provided with finger-pieces 59 and 60 by means of which they may be manipulated to overcome the torsion of the springs 57 and 58 and disconnect the levers 51 and 52 from the casings 12 and 10. The bracket 85 48 also has pivoted thereto another pair of levers 61 and 62 which are pivoted at 63 and 64 to said bracket and are provided at their outer ends with segmental plates 65 and 66, respectively, which bear against the casings 90 29 and 27, respectively. Said segmental plates are held against said casings by torsional springs 67 and 68, respectively. They are provided with finger pieces 69 and 70, whereby the levers 61 and 62 may be operated to overcome the tension of the springs 95 67 and 68 and free the casings 29 and 27 from the clamp plates 65 and 66. It will thus be seen that the two instruments 5 and 6 may be readily attached to, or disconnected from, each other by means of the levers 51 and 52, 61 and 62 and the bracket 48 upon which said levers are mounted.

The instrument is played in the usual manner and by changing the mouth piece 105 upon which the musician plays the variety of tone production hereinbefore set forth may be obtained by one musician, thus greatly increasing the effects which can be produced by a small orchestra.

Having thus described my invention, what I claim and desire by Letters Patent is:

1. In combination, two complete wind instruments of different styles, each of said instruments embodying a plurality of valves and casings therefor and means for detachably fastening one of said instruments to the other, a mouth piece for each of said instruments, said mouth pieces being adjacent to each other, said means comprising a bracket 115 and a plurality of spring-actuated levers mounted on said bracket and adapted to engage said valve casings.

2. In combination, two complete wind instruments of different styles, each of said instruments embodying a plurality of valves and casings therefor and means for detachably fastening one of said instruments to the other, a mouth piece for each of said instruments, said mouth pieces being adjacent 120

125

130

to each other, said means comprising a bracket interposed between the valve casings of said instruments, respectively, and a plurality of spring-actuated levers mounted on 5 said bracket and terminating at one end thereof in segmental curved plates adapted to engage said valve casings.

In testimony whereof I have hereunto set my hand in presence of two subscribing witnesses.

LOUIS F. KLOEPFEL.
